INDUCTION COIL

Giuseppe Rigante, Westerleigh, N. Y., now by
judicial change of name Joseph Luigi Rigandi

Application March 18, 1933, Serial No. 661,503

1 Claim. (Cl. 175—360)

The present invention relates to new and useful improvements in coil structures and more particularly it pertains to induction coils.

It is an object of the invention to provide a new and improved coil structure wherein a plurality of induction coils may be combined in a single unit.

It is a further object of the invention to provide a new and novel structure whereby a tuning of the coil may be accomplished.

Still a further object of the invention resides in the provision of means for completely shielding the coils.

Still a further object of the invention resides in the provision of a single support for the coil and the shield.

Other objects of the invention will appear as the nature of the invention is better understood.

Reference will be had to the accompanying drawings, wherein;

Figure 1 is a longitudinal sectional view of a coil constructed in accordance with one form of the invention,

Figure 2 is a transverse sectional view taken on the line 2—2 of Figure 1.

Figure 3 is a longitudinal sectional view illustrating a slightly modified form of the invention.

Figure 4 is a longitudinal sectional view illustrating a still further modified form of the invention,

Figure 5 is a longitudinal sectional view illustrating a still further modified form of the invention,

Figure 6 is a longitudinal sectional view illustrating a further modified form of the invention the coil in this form of the invention being provided with posts by means of which it may be removably attached to a suitable socket element.

Figure 7 is a longitudinal sectional view of a still further modified form of the invention, and;

Figure 8 illustrates a modified form of the invention in which a plurality of coils are mounted in axial alignment within a common shield building up a plurality of units.

Referring to Figures 1 and 2 of the drawings, the device comprises a core member 10 having end members 11. The core member 10 has a bolt 12 passed therethrough and nuts 13 upon the bolt 12 serve to hold the end members 11 in contact with the ends of the core 10. The end members 11 are provided with grooves or channels 14 and these channels are adapted to receive cylindrical members 15 formed of suitable material the cylindrical members 15 being preferably arranged con-

centrically with the core 10 and with each other. The reference numeral 16 designates a coil which is wound upon the core 10. The reference numerals 17 and 18 designate coils wound upon the cylindrical member 15 said coils 17 and 18 being separated by the outer cylindrical member 15.

The reference numeral 20 designates a shield and said shield is formed with a top wall 21 which has a depression 22 therein. The bolt 12 heretofore mentioned has an extended end 23 which is threaded and this end receives a nut 24 which through the medium of an insulating element 25 clamps the lower wall of the depressed portion in order to secure the coil member to the top wall of the shield 20. The shield also has a base portion 26 to which it is secured as at 27 and a bottom wall 28 through which the threaded extension 23 extends. An insulating member 30 similar to the one heretofore described is carried by the bolt 12 and a nut 31 serves to secure the lower end of the bolt to the bottom wall 28 through the medium of said insulating member 30. The supporting base 26 may have a flange 32 by which it may be adapted to a suitable supporting member such as a panel, baseboard or similar device.

Mounted upon the bolt 12 there is a metal plate 35 and interposed between this metal plate 35 and the top wall 21 of the shield there is a dielectric element 36. A spring 37 tends to force the dielectric element 36 and the plate 35 outwardly against a nut 38 which is threaded upon the end 23 of the bolt 12.

By adjustment of the nut 38 and the consequent positioning of the plate 35 of the dielectric element 36 with respect to the several coils the latter may be tuned.

In the modified form of the invention shown in Figure 3 the reference numeral 40 designates the core. This core has a base 41 which is provided with a plurality of annular shoulders 42 to which a plurality of cylindrical members 43 may be attached by screws or the like 44. The several coils are formed upon the cylindrical members and upon the core as in the form illustrated in Figures 1 and 2.

A shield 45 surrounds this coil structure and said shield is of substantially the same construction as that heretofore described. In this form of the invention, however, the core 40 rests directly upon the bottom wall 47 of the shield and said core has a head extension 48 which is engaged in an opening in the bottom wall of the depressed portion 22 of the shield, the same being inserted through a key slot and turned. In

this form of the invention the bolt 49 is mounted directly in the core member 40, the spring 31, metallic plate 35 and dielectric element 36 being the same as in the heretofore described form of the invention.

The operation of this form of the invention is substantially the same as that form illustrated in Figure 1.

The coil illustrated in Figure 4 is slightly different in construction in that the core member 10 is held between the end members 50 and 51 of the shield 52. For this purpose the end walls 50 and 51 are provided with depressed portions 53 in which channels 54 for the reception of the cylindrical members 55 are formed. The shield 52 in this form of the invention is substantially the same as that heretofore described except as for its end walls. In this form of the invention, however, there is no tuning means provided.

In this last described form of the invention the several leads for the coils have been illustrated as extending through openings 56 in the side wall of the shield and it is to be understood, that although this construction is not illustrated in each of the forms of the invention, this construction may be employed in connection with each of the coils herein illustrated. The reference numeral 57 designates a strip of insulating material suitably secured to the interior of the shield 52 and serves to prevent electrical contact between the leads of the shield.

In that form of the invention illustrated in Figure 5 of the drawings the shield is designated 60 and has a depressed portion 61 in its top wall which is considerably deeper than the depressed portion in the other forms previously described. The core member 62 is secured to the bottom wall of this depressed portion 61 by a spool like member 63 upon which a coil 64 is wound, the bottom wall of the depressed portion 61 being clamped between the spool like member 63 and the core 62 by means of a nut 65 threaded upon the end 66 of a bolt 67 which passes through the core member 62, the bottom wall of the depressed portion 61 and the spool member 63. In this form of the invention the cylindrical members are designated 68 and each has an end wall 69 through which the bolt passes, the cylindrical members being separated by a suitable insulating element 69'. In this form of the invention the coils are wound upon the core member 62 and the cylindrical members 68, the leads extending through openings in the casing as heretofore described but not shown in this figure. In this last described form of the invention the core member, cylindrical members and the coils carried thereby are held suspended from the bottom wall of the depressed portion 61 and within the shield 60.

In the form of the invention illustrated in Figure 6, the core member 70 is provided with a shoulder 71 upon which the cylindrical member 72 is mounted, the shield 73 being mounted upon a shoulder 74 of the core member. The shield has a depressed portion 75 which has a key way slot to receive the head 76 of the core member 70 and a manipulating handle 77 is secured to

the head member 76 of the core 70. In this form one end of the core member 70 forms the closure for one end of the shield 73. Upon this end of the core member 70 there is a plate 78 which carries a plurality of prongs 79 which form the terminals for the leads from the coils 78' and 79' formed respectively on the core 70 and the cylindrical member 72.

The form of the invention illustrated in Figure 7 is substantially the same as that illustrated in Figure 6 except that there are a plurality of cylindrical members 80 and 81, the base of the core 70 being formed with a plurality of shoulders 82 and 83 upon which the cylindrical members 80 and 81 are respectively mounted. Prongs 79 form the terminals of the coil leads in this form of the invention.

In Figure 8 I have shown three coil units mounted in a single shield. The shield comprises three sections 90, 91 and 92. The shields 90 and 92 each have a closed end 93 and an open end 94. The coils are formed upon cylindrical members 95 of which there may be any desired number, which are supported as heretofore described. The shield 91 has two open ends and the open ends of the shields 90 and 92 are adapted to be positioned in end to end relation with the open ends of the shield 91. Partition plates 96 are employed to close both the open end of the shield 90 and 92 and both open ends of the shield 91.

The coil mounted within the shield 90 is suspended from the upper wall 93 thereof by a bolt 97. The coil mounted within the shield 92 is supported from the closed bottom thereof by means of a bolt 98 and the coil mounted within the shield 91 is clamped between the partition plates 96 by a bolt 99. By this construction it is apparent that the several coils are shielded from outside interference and from each other, and it is to be understood that the leads from these several coils will extend through the shields preferably in the same manner as illustrated in Figure 4 of the drawings.

From the foregoing it will be apparent that the present invention provides new and novel coil structures in which a plurality of coils may be carried by a single support and by which an effective shielding of the several coils is had.

Having thus described the invention, what is claimed as new and what it is desired to secure by Letters Patent of the United States, is:

A coil structure comprising in combination, a core of non-conducting material, a plurality of spaced cylindrical members carried by said core, a coil formed on said core, a coil on each of said cylindrical members, a shield completely enclosing said core and said cylindrical members, said shield having a depressed recess in one of its end walls, the bottom wall of said recess having an opening therein, and means carried by the core and adapted for reception in the opening in the bottom wall of the depressed recess for securing the core and the shield together.

GIUSEPPE RIGANTE.
